BALANCED GASOLINE FROM WIDE BOILING NAPHTHA

John W. Herrmann, Elizabeth, and Donald D. MacLaren, Scotch Plains, N.J., assignors to Esso Research and Engineering Company, a corporation of Delaware

Application October 1, 1957, Serial No. 687,498

7 Claims. (Cl. 208—80)

The present invention relates to the reforming of hydrocarbons and particularly to an improved method for upgrading the naphtha fraction from crude oils to produce high octane gasoline having a balanced distribution of high octane components throughout the boiling range of the gasoline. More particularly, it relates to thermally converting the heavy virgin naphtha cut e.g. 260/330° F., hydroforming the intermediate naphtha cut, e.g. 160/260° F., and suitably upgrading the C₅/C₆ cut as by fractionation to separate isopentane, isomerization, thermal conversion with or without C₃/C₄ alkylation, or steam cracking. In addition an alkylation process for the lighter components from the 160/260° F. hydroforming and 260/330° F. thermal conversion operations may be used.

The present invention solves a very real problem. Straight hydroforming produces a gasoline in which the components in the higher boiling half of the total boiling range have a much higher octane rating than do the lower boiling components in the "front end" of the gasoline. This concentration of O.N. in the "back end" of the gasoline is known in the industry to give poor octane distribution and poor car performance in certain critical European cars. By the present invention the "front end" octane deficiency is solved by a process that uses the same fraction of the crude as was previously treated by hydroforming, and from this produces a balanced gasoline of high octane rating. Thus, by the present process it is not necessary to build up front end octane rating by adding in valuable components obtained from other fractions of the crude, e.g. from cracking heavier oils. This is particularly important in those regions where the greater demand for fuel oil over gasoline makes heavier fractions of the crude more valuable than in those regions where there is a greater demand for gasoline.

Hydroforming may be defined as an operation in which a naphtha is contacted at elevated temperatures and pressures, in the presence of hydrogen with a solid catalytic material. As is known, hydroforming is an operation which involves dehydrogenation of naphthenes to form the corresponding aromatics, isomerization of paraffins and carbocyclic compounds, some aromatization of paraffins and hydrocracking of the higher boiling paraffins. The process results in the production of sufficient hydrogen to supply the requirements of the hydroforming operation and is usually a net producer of hydrogen.

Thermal conversion is a cracking operation carried out in the absence of a catalyst to improve the octane number and volatility of virgin naphtha. As such conversion is usually carried out, the virgin naphtha is charged to a once-through coil only cracking operation at 750–1000 p.s.i.g., with the maximum temperature reached in the coil being about 1100° F. The cracked product is quenched and discharged into a tar separator where polymer boiling above 400° F. is removed.

Isomerization is a process in which hydrocarbons boiling substantially in the gasoline range are subjected, in the presence of a catalyst, to heat treatment in the liquid

2

or vapor phase to produce a product containing isomeric forms of the hydrocarbons.

Steam cracking is a process conducted preferably at low pressure in the range of 50–100 p.s.i.g. utilizing about 5 75 wt. percent steam to produce a 30–40 wt. percent conversion to dry gas. A highly olefinic product is obtained by this process.

Alkylation is a process for the chemical addition of C₃, C₄, or C₅ olefins or mixtures of these olefins to an isoparaffin, usually isobutane. The alkylation reaction can be promoted by concentrated sulfuric acid, hydrofluoric acid, aluminum chloride or boron chloride at low temperatures. Thermal alkylation is possible at high temperatures and very high pressures.

15 The present invention will be more clearly understood by reference to the accompanying drawings. Figure I diagrammatically represents one system for processing the whole naphtha fraction from crude. Figure II depicts a more complex processing scheme incorporating an 20 alkylation step utilizing the proper components in the light ends from thermal cracking and hydroforming which have been separated by the use of 5 Å. molecular sieves.

The use of molecular sieves is a rather new commercial development in the petroleum refining art. It has, of 25 course, been known for some time that certain zeolites, both naturally occurring and synthetic and sometimes termed molecular sieves, have the property of separating straight chain from branch chain hydrocarbon isomers as well as from cyclic and aromatic compounds. These 30 zeolites have innumerable pores of uniform size and only molecules small enough to enter the pores can be adsorbed. The pores may vary in diameter from 3 Å. or 4 Å. to 15 Å. or more, but it is a property of these 35 zeolites or molecular sieves that any particular product has pores of substantially uniform size.

The scientific and patent literature contains numerous 40 references to the adsorbing action of natural and synthetic zeolites. Among the natural zeolites having this sieving property may be mentioned chabazite. A synthetic 45 zeolite with molecular sieve properties is described in U.S. Pat. 2,442,191. Zeolites may vary somewhat in composition but generally contain the elements silicon, aluminum and oxygen as well as an alkali and/or an alkaline earth element e.g. sodium and/or calcium. The naturally occurring zeolite analcrite, for instance, has the empirical formula NaAlSi₂O₆·H₂O. Barrer (U.S. 2,306,610) teaches that all or part of the sodium is replaceable by calcium to yield on dehydration a molecular sieve having the formula (Ca, Na₂)Al₂Si₄O₁₂. Black (U.S. 50 2,552,426) describes a synthetic molecular sieve zeolite having a formula 4CaO·Al₂O₃·4SiO₂. A large number of other naturally occurring zeolites having molecular sieve 55 activity i.e. the ability to adsorb straight chain hydrocarbons and exclude or reject the branch chain isomers and aromatics because of differences in molecular size are described in an article, entitled "Molecular Sieve Action of Solids," appearing in Quarterly Review, vol. III, pages 293–320 (1949), published by the Chemical Society (London).

60 A 5 Å. molecular sieve may be prepared by rapidly mixing an aqueous solution of sodium metasilicate and an aqueous solution of a sodium aluminate at a temperature of about 180° F. in proportions such that the mixture has a ratio of SiO₂·Al₂O₃ of about 1.5 to 1. A precipitate forms instantaneously of the desired crystalline sodium aluminum silicate which is then withdrawn and treated with an aqueous solution of calcium chloride to replace at least a portion of the sodium content of said material with calcium. The material is then calcined to obtain the desired 5 Å. synthetic molecular sieve 65 zeolite.

70 Referring to Figure I, a naphtha boiling up to about

330° F. is supplied through line 1 to distillation column 2. From column 2 a 260/330° F. bottoms cut is passed through line 3 to thermal conversion 4. Thermal conversion is conducted at pressures of 100 to 1000 p.s.i.g. and at temperatures of 1000° to 1200° F. The thermal conversion product after suitable separation of tar and the C₃ and lighter gas is passed through line 5 to join other process naphthas in line 6. The C₅/C₆ cut from column 2 is passed through line 10 to fractionator 11 where isopentane is separated as the overhead which is passed through line 12 also to join the other products in line 6. The middle cut boiling from about 160/260° F. is passed through line 7 to hydroforming 8 and the hydroformate is passed through line 9 also to line 6. A balanced, high octane gasoline is so obtained.

Referring to Figure II, a diagrammatic representation of an alternate process for carrying out this invention, a virgin naphtha boiling up to about 330° F. is passed through line 15 to distillation column 16 wherein as before the cuts are segregated. The middle boiling 160°-260° F. cut is passed through line 17 to hydroforming 18 which is operated under similar conditions to those described in connection with Figure I. Hydroformate is passed through line 19 to debutanizer column 20. Propane, normal butane and isobutane are taken overhead through line 21 to moving bed molecular sieve adsorption zone 22. Conventional fixed bed molecular sieve operations may also be utilized in this invention. Molecular sieve zone 22 is operated at pressures of 0 to 500 p.s.i.g. and temperatures of 100° to 500° F. In zone 22 the normal paraffins in the feed are picked up by the sieve displacing at the same time straight chain olefins which are on the sieve material entering from the desorption zone through line 23. The non-normal components pass overhead along with the displaced olefins through line 24 to alkylation process 25. Alkylation is conducted at temperatures of about 40° F., pressure of 0 to 10 p.s.i.g., utilizing 98% sulphuric acid for the fresh catalyst. From alkylation the product is passed through line 26 to join other products of the processes in line 27, and so form a balanced high octane gasoline. From molecular sieve adsorption zone 22 sieve plus adsorbed propane and normal butane are passed through transfer device 28 to molecular sieve desorption zone 29, operating under slightly higher than adsorption temperatures of 200° to 600° F. and pressures of 0 to 450 p.s.i.g.

Referring now back to column 16, the 260°-330° F. bottoms fraction is passed through line 30 to thermal conversion zone 31 which is conducted under similar conditions to those described in connection with Figure I. Thermal conversion product is passed through line 32 to column 33 where a highly olefinic C₃-C₄ cut is taken overhead. Column 33 is a diagrammatic representation of a two column system. The first column removes the ethane and lighter components overhead and the second column takes overhead the highly olefinic C₃-C₄ cut. This overhead is passed through line 34 to molecular sieve desorption zone 29 where it desorbs the sieve of the

C₃-C₄ normal hydrocarbons adsorbed in zone 22. The raffinate stream containing C₃ and C₄ normal hydrocarbons desorbed from the sieve is passed from the process through line 35. The sieve containing adsorbed olefins is passed through line 23 back to adsorption zone 22, as previously described. From the bottom of column 33 the C₅+ thermal conversion product is passed through line 36 to join the other process products in line 27. From column 16 the overhead C₅-C₆ stream is passed through line 37 to distillation column 38 where high octane isopentane is separated as the overhead and the lower octane hydrocarbons are passed from the bottom of the column through line 39. The isopentane overhead is passed through line 40 to join the other process gasoline components in line 27. If desired, instead of the column 38 fractionation to separate isopentane treatment of the C₅-C₆ stream, this fraction may be subjected to isomerization, thermal conversion with or without C₃-C₄ alkylation, steam cracking or other processing.

20 The following example presented in tabular form is illustrative of the present invention.

Example

In the following table three processes for carrying out the present invention are compared with the best prior art process for treating a wide boiling naphtha.

In the prior art design steam cracking of the C₅/C₆ fraction is conducted at 1440° F. temperature; 20 p.s.i.g. pressure; 80 wt. percent steam and 57.5% conversion to dry gas. The 160/260° F. cut is processed by fixed bed platinum hydroforming in the presence of a catalyst containing 0.6 wt. percent of platinum deposited on activated alumina at 900° F. temperature, 300 p.s.i.g. pressure in the presence of 6000 ft.³ of hydrogen/barrel of feed, and a feed rate of 1.8 wts. of feed per hour per weight of catalyst. The 260/360° F. cut is also processed by fixed bed platinum hydroforming in the presence of a catalyst containing 0.6 wt. percent of platinum deposited upon activated alumina. The conditions are: 900° F. temperature; 300 p.s.i.g. pressure in the presence of 6000 ft.³ of hydrogen/barrel feed, and a feed rate of 3.2 wts. of feed per hour per weight of catalyst.

In the heavy naphtha thermal conversion combination process the C₅/C₆ cut is fractionated at 20 p.s.i.g. pressure, the overhead cut boiling in the range of 80° to 100° F. The 160/260° F. cut is platinum reformed under the same conditions as in the prior art design described above. Thermal conversion of the 260/330° F. cut is conducted at 1100° F. temperature and 200 p.s.i.g. pressure.

In the heavy naphtha conversion+C₃/C₄ alkylation process alkylation of the C₃/C₄ fraction is conducted in the presence of a 98 wt. percent sulphuric acid catalyst at 40° F. temperature and 7 p.s.i.g. pressure. 0.07 vol. of olefin/hr./vol. acid and 0.8# H₂SO₄/gal. alkylated catalyst are consumed. Treatment of the other cuts is as described above for the heavy naphtha thermal conversion combination process.

TABLE

Base	Prior Art Design	Heavy Naphtha Thermal Conversion	Heavy Naphtha Thermal Conv.+C ₃ /C ₄ Alkylation	Heavy Naphtha Thermal Conv.+C ₃ /C ₃ Alkylation
C ₅ /C ₆ 160/260° F.	Steam Crkg. (80 RON)..... Plat. Ref. (97.5 RON).....	Fract. (80 RON)..... Plat. Ref. (97.5 RON).....	Fract. (80 RON)..... Plat. Ref. (100 RON).....	Fract. (80 RON)..... Plat. Ref. (100 RON).....
260/330° F.	Plat. Ref. (80 RON).....	Thermal Conv. (81 RON).....	Thermal Conv. (81 RON).....	Thermal Conv. (81 RON).....
Alkyl. Stock			C ₃ /C ₄ Alkyl. (94.8 RON).....	C ₂ /C ₃ Alkyl. (95.1 RON).....
Regular Gasoline: Res. O.N.+1.5 cc. TEL..... Res. O.N. on Front 75% (Equals Road O.N.)	91.6..... 79.8.....	92.3..... 86.9.....	(1.1 cc. TEL) 92.2..... 88.3.....	92.9..... 88.0.....
Premium Gasoline: Res. O.N.+1.5 cc. TEL..... Res. O.N. on Front 75% (Equals Road O.N.)	100.5..... 91.5.....	100.5..... 91.5.....	100.0..... 93.0.....	100.0 (clear)..... 94.5.....

In the heavy naphtha thermal conversion +C₂/C₃ alkylation process C₂/C₃ cut alkylation is conducted in the presence of aluminum chloride catalyst at 120° F. temperature and 400 p.s.i.g. pressure and 2.25# AlCl₃/bbl. alkylate catalyst consumption. Treatment of the other cuts in this process are also as described above for the heavy naphtha thermal conversion process.

As can be seen from the above chart the heavy naphtha thermal reforming combination process gives a road octane increase of 7 numbers for regular gasoline with an 0.7 research octane number increase over that of the prior art design. The different C₅/C₆ treatment used in the prior art design does not affect the validity of this comparison of road octanes since all of the product from this light fraction gets into the "front end" and is 80 octane no matter by which process it is produced. There is no improvement in the premium gasoline over the prior art design because in this example the premium was obtained entirely from platinum hydroforming of the 160/260° F. cut. In these particular examples, equal amounts of premium and regular gasolines are secured by the design of the process. It should also be noted that additional improvement in road octane may be provided by incorporating C₃/C₄ or C₂/C₃ alkylation processing of light components available from the process. In this respect looking at the chart it can be seen that C₂/C₃ alkylation gives a greater increase in road octane for the premium gasoline than does C₃/C₄ alkylation and less of an increase for the regular gasoline than does C₃/C₄ alkylation. It would seem that C₂/C₃ alkylation would be the preferred process based on balancing road octane appreciation obtainable between the two grades but other factors such as the value of the raw materials for other uses and the relative costs of the C₃/C₄ as compared to the C₂/C₃ alkylation processes would have to be considered and might well be controlling.

It is to be understood that this invention is not limited to the specific example above which has been offered merely as an illustration and that modifications may be made without departing from the spirit of this invention.

What is claimed is:

1. The process for producing from a wide boiling naphtha a balanced high octane gasoline having high octane components distributed throughout its boiling range which comprises distilling to separate C₅/C₆, 160/260° F. and 260/330° F. fractions; suitably upgrading the C₅/C₆ low boiling fraction, hydroforming the fraction boiling from about 160/260° F., and thermally converting the fraction boiling from about 260/330° F.; and combining C₅/C₆ upgraded product with the hydroformate and with the thermal conversion product to produce the desired gasoline.

2. The process for producing from a wide boiling naphtha a balanced high octane gasoline having high octane components distributed throughout its boiling range which comprises distilling to separate C₅/C₆, 160/260° F. and 260/330° F. fractions; fractionating the C₅/C₆ low boiling fraction to separate high octane isopentane, hydroforming the fraction boiling from about 160/260° F., and thermally converting the fraction boiling from about 260/330° F.; and combining the isopentane with the hydroformate and with the thermal conversion product to produce the desired gasoline.

3. The process for producing from a wide boiling naphtha, a balanced high octane gasoline having high octane components distributed throughout its boiling range which comprises distilling to separate C₅/C₆, 160/260° F., and 260/330° F. fractions, steam cracking the C₅/C₆ low boiling fraction, hydroforming the fraction boiling from about 160/260° F. and thermally converting the fraction boiling from about 260/330° F.; and combining C₅/C₆ cracked product with the hydroformate and with the thermal conversion product to produce the desired gasoline.

4. The process for producing from a wide boiling

naphtha a balanced high octane gasoline having high octane components distributed throughout its boiling range which comprises distilling to separate C₅/C₆, 160°/260° F. and 260°/330° F. fractions; fractionating the C₅/C₆ low boiling fraction to separate high octane isopentane, hydroforming the fraction boiling from about 160/260° F. and thermally converting the fraction boiling from about 260/330° F.; fractionating the hydroformate to separate overhead propane, normal butane and isobutane, molecular sieving this overhead to remove propane and normal butane on the sieve, passing the mainly isobutane raffinate to alkylation; passing thermal conversion product to fractionation to separate overhead a highly olefinic C₃/C₄ cut, molecular sieving this overhead to separate olefins, and passing said olefins to join previously separated isobutane in an alkylation step, alkyllating; and combining isopentane separated from the C₅/C₆ cut with hydroformate with thermal conversion product and with the alkyllate to produce the desired balanced gasoline.

5. The process for producing from a wide boiling naphtha a balanced high octane gasoline having high octane components distributed throughout its boiling range which comprises distilling to separate C₅/C₆, 160°/260° F. and 260°/330° F. fractions; fractionating the C₅/C₆ low boiling fraction to separate high octane isopentane, hydroforming the fraction boiling from about 160°/260° F. and thermally converting the fraction boiling from about 260°/330° F.; fractionating the hydroformate to separate overhead propane, normal butane and isobutane, molecular sieving this overhead to remove propane and normal butane on the sieve, passing mainly isobutane raffinate to alkylation; passing thermal conversion product to fractionation to separate overhead a highly olefinic C₂/C₃ cut, molecular sieving this overhead to separate olefins, and passing said olefins to join previously separated isobutane in an alkylation step, alkyllating; and combining isopentane separated from the C₅/C₆ cut with hydroformate, with the thermal conversion product and with the alkyllate to produce the desired balanced gasoline.

6. The process for producing from a wide boiling naphtha a balanced high octane gasoline having high octane components distributed throughout its boiling range which comprises distilling to separate C₅/C₆, 160/260° F. and 260/330° F. fractions; fractionating the C₅/C₆ low boiling fraction to separate high octane isopentane, hydroforming the fraction boiling from about 160/260° F. and thermally converting the fraction boiling from about 260/330° F.; fractionating the hydroformate to separate overhead propane, normal butane and isobutane, passing this overhead over molecular sieves containing adsorbed C₃/C₄ olefins, passing the combined desorbed olefins from said sieve and isobutane raffinate to alkylation; passing thermal conversion product to fractionation, separating overhead a highly olefinic C₃/C₄ cut, passing this overhead over sieves containing propane and normal butane from the above described sieve treating zone, separating olefins adsorbed on the sieve, passing sieve containing adsorbed olefins to the first described molecular sieve treating zone, alkyllating; and combining isopentane separated from the C₅/C₆ cut with hydroformate with thermal conversion product and with alkyllate to produce the desired balanced gasoline.

7. The process for producing from a wide boiling naphtha a balanced high octane gasoline having high octane components distributed throughout its boiling range which comprises distilling to separate C₅/C₆, 160/260° F. and 260/330° F. fractions; fractionating the C₅/C₆ low boiling fraction to separate high octane isopentane, hydroforming the fraction boiling from about 160/260° F. and thermally converting the fraction boiling from about 260/330° F.; fractionating the hydroformate to separate overhead propane, normal butane and isobutane, passing this overhead over molecular sieves containing adsorbed C₂/C₃ olefins, passing the combined desorbed olefins from said sieve and isobutane raffinate to alkylation; passing

thermal conversion product to fractionation, separating overhead a highly olefinic C₂/C₃ cut, passing this overhead over sieves containing propane and normal butane from the above described sieve treating zone, separating olefins adsorbed on the sieve, passing sieve containing adsorbed olefins to the first described molecular sieve treating zone, alkylating and combining isopentane separated from the C₅/C₆ cut with hydroformate with thermal conversion product and with alkylate to produce the desired balanced gasoline.
